LASTING MACHINE

William S. Dallas, Beverly, Mass., assignor to
 United Shoe Machinery Corporation, Borough
 of Flemington, N. J., a corporation of New
 Jersey

Application August 12, 1939, Serial No. 289,891

13 Claims. (Cl. 12—14)

This invention relates to lasting machines and is herein illustrated as embodied in a machine particularly adapted to the lasting of prewelt shoes.

In lasting prewelt shoes in a machine of the type herein illustrated, the margin of an upper with a welt attached is wiped inwardly over the bottom of a last, or an insole thereon, to an extent determined ordinarily by the distance between the edge of the last bottom and the edge face of a filler, which in some cases is temporarily attached to the last bottom and in other cases is secured to an insole attached to the last bottom. Prewelt lasting machines of the type herein illustrated are provided with lasting wipers, the wiping edges of which conform to the shape of the periphery of that portion of the upper on which they operate. The wipers in their operation should advance uniformly over the margin of the last bottom to last the upper to the same extent about its entire periphery. In lasting machines heretofore employed a uniform lasting of the welted margin of the upper depends upon accurate location of the last relatively to the lasting wipers, since the range of movement of the wipers is fixed and unchangeable. It is difficult in a machine of this type to locate the last accurately relatively to the lasting wipers, since there are no gages other than the wipers themselves to guide the operator. Consequently, in the commercial manufacture of prewelt shoes, the lasting of the uppers has not been as accurate as desired.

It is an object of the present invention to provide a lasting wiper organization in a prewelt lasting machine which permits the wipers to accommodate themselves to the position of the last in the machine and enables the operator to wipe the welted margin inwardly to a uniform extent over the margin of the last bottom even though the last is not located exactly in the center of the space between the wipers.

The lasting machine organization herein illustrated includes a pair of wipers constructed and arranged to operate on one end portion of a prewelt upper. In order to obtain a high degree of accuracy in the lasting operation, it is desirable that the wipers be located by engagement with an end portion of the shoe before their closing action commences, since the position of the shoe in the machine lengthwise thereof may vary slightly. Accordingly, it is a further object of the invention to provide a lasting organization in which the wipers are located relatively to a

shoe in the machine before their closing action commences.

With the above objects in view, the invention, in one aspect, consists in the provision in a prewelt lasting machine having end lasting wipers which conform to the shape of the periphery of the shoe of mechanism for advancing and closing the wipers, which mechanism permits independent closing movement of either wiper after the closing movement of the other has been arrested by engagement with the shoe, and means for preventing the closing of the wipers until the wipers have entered the welt crease at one end of the shoe and are located thereby for closing movement on the shoe. The illustrated wipers first advance lengthwise of the shoe while held wide open until the adjacent end portions of their wiping edges enter the welt crease at one end of the upper and wipe that end portion of the upper over the margin of the last bottom and against the edge face of a filler. The resistance of the upper to further advancement of the wipers lengthwise of the shoe arrests their lengthwise movement, and thereupon the wipers close upon the upper to last the side portions thereof, swinging about a common center located at the adjacent ends of their wiping edges. For guiding the closing movement of the wipers, the illustrated machine is provided with a plate having wiper-guiding members, which plate moves with the wipers during their movement lengthwise of the shoe and is arrested when the lengthwise movement of the wipers is arrested, whereupon the wiper actuator advances relatively to the wiper-guiding plate and closes the wipers on the upper.

In the operation of the wipers, if the last is not located exactly in the center of the space between the wipers, and therefore one wiper completes its closing movement with the closing movement of the other wiper not completed, the illustrated wiper-operating mechanism operates the latter wiper independently of the former and completes its closing movement.

These and other features of the invention will now be described with reference to the accompanying drawings and pointed out in the appended claims.

In the drawings,

Fig. 1 is a plan view of the heel end of a bed lasting machine embodying the features of the present invention, certain parts being broken away to illustrate underlying parts some of which are shown in section;

Fig. 2 is a sectional elevation on the line II—II of Fig. 1;

Fig. 3 is a section on the line III—III of Fig. 1;

Fig. 4 is a plan view of the heel lasting wipers and their operating mechanism, certain parts being broken away to illustrate underlying parts some of which are shown in section; and

Fig. 5 is a section on the line V—V of Fig. 4.

Referring to Fig. 1, the illustrated machine is provided with a heel head 10 which in its general organization is similar to constructions found in well-known types of bed lasting machines such, for example, as that shown in United States Letters Patent, No. 1,018,477, granted February 27, 1912, on an application of Matthias Brock. The heel head 10 includes a cylindrical portion 12 which is mounted in bearing brackets 14 for turning movement about an axis extending longitudinally of a shoe in the machine. The heel head 10 carries the heel lasting wiper organization which in the construction herein shown comprises a pair of lasting wipers 16 the wiping edges of which conform to the shape of the periphery of the rear part of a shoe, carriers 18 (Fig. 4) to which the wipers are secured by screws 20, and a plate 22 (Fig. 1) which carries wiper guiding rolls hereinafter identified and which has a longitudinal tongue 24 which fits into a groove in a cover plate 26 and directs the movement of the plate 22 in a rectilinear path toward and from the heel end of a shoe in the machine. The illustrated wipers have thin beveled wiping edges which facilitate their entrance into the welt crease of a prewelt upper.

The illustrated lasting wipers in the course of their operation first move forwardly toward the heel end of a shoe in the machine, while they are held in their open position, until the adjacent end portions of the wiping edges of the wipers engage and overwipe the back seam portion of the upper. Upon the completion of the back seam lasting the forward movement of the wipers is arrested by the shoe itself and the wipers close upon the shoe to last the opposite sides of the heel and shank portions. For guiding the closing movement of the wipers the plate 22 has downwardly extending studs 28 (Fig. 1) on which are pivoted rolls 30 (Fig. 4), said rolls being arranged in arcuate slots 32 provided in the wiper carriers 18 and being supported upon the base of the heel head. The slots 32 are concentric with each other, their common center being located at the adjacent ends of the wiping edges of the wipers 16. For operating the wipers the illustrated organization is provided with a hand lever 36 which is fulcrumed at 38 on a swinging arm 39 and is pivoted at 40 to a block 42 swiveled on a shaft 44. Referring to Fig. 2, the left end of the shaft 44 is provided with a head 46 which is grooved transversely to receive the central portion of a crossbar 48, the crossbar being pivoted to the head 46 by a pin 50 having a flat head which is confined in a groove 52 in the bottom of the plate 22 for a purpose hereinafter described. The crossbar 48 is connected to the wiper carriers 18 by links 54 (Fig. 4). The crossbar is normally held at right angles to the shaft 44 by a T-shaped pin 56 the crosshead of which is positioned in the groove in the head 46 of the shaft 44 and the stem of which is slidably mounted in a lengthwise bore 58 provided in the shaft and communicating with said groove. The crosshead of said pin is pressed against the crossbar 48 by a spring 60 in said bore, thus yieldingly maintaining the normal position of the crossbar. When the hand

lever 36 is operated the shaft 44 moves to the left as seen in Fig. 1 and after the wipers overwipe the back seam portion of the upper, the plate 22 comes to rest, but the crossbar 48 continues to advance and close the wipers 16 in unison. In the event that one of the wipers comes to the limit of its overwiping movement before the other, the crossbar 48 swings about its connection with that wiper-link 54 which has completed its operation, and imparts an independent closing movement to the other wiper. Thus, it will be seen that any inaccuracies in the construction of the upper or in the spacing of opposite sides of the shank portion of the upper relatively to the wipers will not prevent a complete lasting of both sides of the shoe by the illustrated wipers. During the forward movement of the wipers, prior to their closing action, the wipers are held open as illustrated in Fig. 1 by the action of a spring 62 mounted in a longitudinal bore 64 in the cylindrical portion 12 of the heel head 10. One end of the spring acts against a plunger 66 in the bore 64, the plunger abutting against the plate 22. The opposite end of the spring acts against a collar 68 secured to the shaft 44. The spring holds the plate 22 in its position relatively to the wipers 16 and the shaft 44 illustrated in Figs. 1 and 2, this position being determined by the engagement of the flat head of the pin 50 with the plate at the right end of the groove 52 in the plate. With the parts in this relation, the shaft 44 which carries the wiper-operating crossbar 48 is at the limit of its retractive movement and the wipers are wide open. During the first stage of the advancement of the wipers, the plate 22, together with the wipers 16 and their operating mechanism, advance as a unit, their relative positions being maintained by the spring 62. After the wipers engage the back-seam portion of the upper and their forward movement is arrested, further movement of the shaft 44 advances the crossbar 48 relatively to the plate 22 and closes the wipers, the spring 62 being compressed to accommodate such movement of the shaft.

For preventing excessive bodily movement of the wiper assembly when there is no shoe in the machine, a pin 70 (Fig. 2) extends downwardly from the cover plate 26 into a short groove 72 in the plate 22. This groove 72 is of such a length that it accommodates the forward movement of the wiper assembly required for the lasting operation but it prevents the heel wipers from striking the toe lasting wipers when the heel wipers are operated without a shoe in the machine.

In the course of the operation of the wipers 16 a considerable force in the direction of the width of the shoe must be imparted to the wipers in order to last the shank portions of the shoe. It is, of course, undesirable for this pressure to be taken by the rolls 30 as this would cause excessive wear and a hard wiper action. Accordingly, the carriage 10 is provided with screws 74 (Figs. 4 and 5) which act against angular blocks 75 which provide abutments for the arcuate edge faces 76 of the wiper carriers 18. The edge faces 76 are concentric with the slots 32 in the wiper carriers and the blocks 75 are so arranged that their abutment faces are positioned in the arc defined by the edge faces 76 and engage said edge faces during the entire closing movement of the wipers. To permit the blocks 75 to be maintained in the desired relation to the carriers 18 as their abutment faces become worn in the operation of the machine they may be conveniently

ently adjusted by advancing the screws 14, lock nuts 18 being provided to secure the screws in adjusted position.

The heel portion of the upper is shaped about its last by a heel band 80 (Fig. 2) of well-known construction. For adjusting the heel band lengthwise of the shoe relatively to the wipers 16 the machine is provided with a mechanism similar to that illustrated and described in United States Letters Patent No. 1,188,617, granted June 27, 1916, on an application of Matthias Brock. Referring to Fig. 2, the illustrated heel band adjusting mechanism comprises a screw-ended shaft 82 mounted in a bore in the cylindrical portion 12 of the head and held against longitudinal movement by a plate 86 secured to the head. The threaded end 84 of the shaft 82 operates in a lug 88 extending downwardly from a slide 90 which carries the heel band supporting mechanism.

In lasting prewelt shoes in the illustrated machine a prewelt upper which has been positioned on its last and pulled over (for example, by means of a machine such as that illustrated and described in United States Letters Patent No. 2,081,228, granted May 25, 1937, on an application of Karl Engel) is mounted on the jack (not shown) and the welt is arranged to overlie the margin of the lasting wipers 16. The jack is then operated to force the shoe rearwardly into the heel band, whereupon the hand lever 36 is operated to advance the lasting wipers. The wipers move forward wide open for a short distance, probably not more than $\frac{1}{4}$ ", until the adjacent ends of their wiping margins have lasted the back seam portion of the upper. The wipers then close on the upper without further forward movement. In the event that one of the wipers comes to the limit of its closing movement before the wiper at the other side of the upper has completed its lasting operation the latter wiper closes independently as hereinbefore described to complete the lasting operation.

Having thus described the invention, what I claim as new and desire to secure by Letters Patent of the United States is:

1. In a lasting machine, a pair of end lasting wipers the wiping edges of which conform to the shape of the periphery of an end portion of a shoe, means for moving the wipers forwardly lengthwise of a shoe supported in the machine, and mechanism through which said means operates to close the wipers upon the shoe after the forward movement of the wipers has been arrested by the shoe, said mechanism being constructed to effect independent closing movement of either wiper after the closing movement of the other wiper has been arrested by the shoe.

2. In a lasting machine, a pair of end lasting wipers the wiping edges of which conform to the shape of the periphery of an end portion of a shoe, means for moving the wipers forwardly lengthwise of a shoe supported in the machine, and mechanism through which said means operates to close the wipers upon the shoe after the forward movement of the wipers has been arrested by the shoe, said mechanism including a wiper-guiding member for directing the closing movement of the wipers which member moves with the wipers during their forward movement lengthwise of the shoe.

3. In a lasting machine, a pair of end lasting wipers the wiping edges of which conform to the shape of the periphery of an end portion of a shoe, means for moving the wipers forwardly

lengthwise of a shoe supported in the machine, and mechanism through which said means operates to close the wipers upon the shoe after the forward movement of the wipers has been arrested by the shoe, said mechanism including a wiper-guiding member for directing the closing movement of the wipers which member moves with the wipers during their forward movement lengthwise of the shoe, and said mechanism being constructed to effect independent closing movement of either wiper after the closing movement of the other wiper has been arrested by the shoe.

4. In a lasting machine, a pair of end lasting wipers the wiping edges of which conform to the shape of the periphery of an end portion of a shoe, means for moving the wipers forwardly lengthwise of a shoe supported in the machine, and mechanism through which said means operates to close the wipers upon the shoe, said mechanism being rendered operative by resistance of the shoe to the forward movement of the wipers.

5. In a lasting machine, a pair of end lasting wipers the wiping edges of which conform to the shape of the periphery of an end portion of a shoe, an actuator, mechanism through which said actuator operates to close the wipers upon the shoe comprising a wiper guiding plate and connections from the actuator to the wipers, said plate and said connections being constructed and arranged to move forwardly lengthwise of the shoe with the wipers until the shoe itself resists further forward movement of the wipers and causes the wiper-operating mechanism to close the wipers on the shoe.

6. In a lasting machine, a pair of end lasting wipers the wiping edges of which conform to the shape of the periphery of an end portion of a shoe, means for moving the wipers forwardly lengthwise of a shoe supported in the machine, and mechanism through which said means operates to close the wipers upon the shoe after the forward movement of the wipers has been arrested by the shoe, said mechanism including a wiper-guiding member for directing the closing movement of the wipers which member moves with the wipers during their forward movement lengthwise of the shoe and holds the wipers open during such forward movement.

7. In a lasting machine, a pair of end lasting wipers the wiping edges of which conform to the shape of the periphery of an end portion of a shoe, an actuator for moving the wipers forwardly lengthwise of a shoe supported in the machine, and a wiper-guiding plate having roll and slot connections with the wipers through which plate the actuator operates to close the wipers upon the shoe after their forward movement has been arrested by the shoe.

8. In a lasting machine, a pair of end lasting wipers the wiping edges of which conform to the shape of the periphery of an end portion of a shoe, an actuator for moving the wipers forwardly lengthwise of a shoe supported in the machine, a wiper-guiding plate having roll and slot connections with the wipers through which plate the actuator operates to close the wipers upon the shoe after their forward movement has been arrested by the shoe, and operating connections from the actuator to the wipers constructed and arranged to permit closing movement of either wiper after the closing movement of the other wiper has been arrested by the shoe.

9. In a lasting machine, a pair of end lasting wipers the wiping edges of which conform to the

- shape of the periphery of an end portion of a shoe, said wipers being constructed and arranged for forward movement lengthwise of the shoe in their open position and for closing movement about a common center located at the adjacent ends of their wiping edges after their forward movement has been arrested by the shoe, and a wiper-guiding plate for directing the closing movement of the wipers, said plate being mounted for forward movement with the wipers.
10. In a lasting machine, a pair of end lasting wipers the wiping edges of which conform to the shape of the periphery of an end portion of a shoe, an actuator for advancing and closing the wipers, a movable plate having roll and slot connections with the wipers for directing their closing movement, and yielding means for holding the plate and the wipers in a predetermined relation to each other and to the actuator as the wipers advance such that the wipers are held in an open position until they engage one end of a shoe in the machine.
11. In a lasting machine, a pair of lasting wipers the wiping edges of which conform to the shape of the periphery of the heel and shank portions of a shoe and the wiping edges of which are constructed to operate in the welt crease of a prewelt upper, means for moving the wipers forwardly lengthwise of a shoe supported in the machine, and mechanism through which said

means operates to close the wipers upon the shoe, said mechanism being rendered operative by resistance of the shoe to the forward movement of the wipers.

12. In a lasting machine, a pair of end lasting wipers the wiping edges of which conform to the shape of the periphery of the end portion of a shoe, a slide for advancing and closing the wipers, a movable plate having a roll and slot connections with the wipers for directing their closing movement, and a spring arranged to operate in opposite directions on the plate and the shaft for holding them at the limit of their relative movement in one direction, the wipers being in their open position when the shaft and plate are at said limit of their relative movement.

13. In a lasting machine, a pair of end lasting wipers, an actuator for moving the wipers forwardly lengthwise of a shoe in the machine and closing the wipers, connections from the actuator to the wipers comprising a slide, a crossbar pivoted on the slide and yieldingly held in a predetermined angular relation to the slide, members connecting the crossbar to the wipers, and yielding means for holding the wipers in an open position during their forward movement, the closing of the wipers depending upon the resistance of the shoe itself to their forward movement.

WILLIAM S. DALLAS. 30
